Primary Examiner—Selina Sikder*(74) Attorney, Agent, or Firm*—Connolly Bove Lodge & Hutz LLP(57) **CLAIM**

We claim the ornamental design for an electrical circuit breaker, as shown and described.

DESCRIPTION

FIG. 1 is a perspective view of the electrical circuit breaker showing our new design;

FIG. 2 is a front elevational view thereof;

FIG. 3 is a side elevational view therof; and,

FIG. 4 is a top view thereof.
